UNITED STATES PATENT OFFICE.

GEORGE IRA SHUMAKER, OF LONGPOINT, IOWA.

MAIL-BAG HOLDER.

1,140,006.

Specification of Letters Patent. Patented May 18, 1915.

Application filed May 11, 1914. Serial No. 837,789.

To all whom it may concern:

Be it known that I, GEORGE IRA SHUMAKER, a citizen of the United States, residing at Longpoint, in the county of Tama 5 and State of Iowa, have invented certain new and useful Improvements in Mail-Bag Holders, of which the following is a specification.

This invention relates to devices for holding mail bags suspended from a crane or similar support, to be caught by a moving train, and its object is to provide a novel and improved device of this kind which is simple in construction and which securely 10 holds the bag or pouch and releases the same without strain thereon. This object is attained by a combination and arrangement of parts to be hereinafter described and claimed, reference being had to the accompanying drawing, in which—

Figure 1 is a horizontal section of the device, and Fig. 2 is a perspective view thereof.

Referring specifically to the drawing, the 25 bag-holding device comprises a body portion 5 carrying a hook 6 and a guard 7 for the latter. The part 5 is rigidly secured to the crane arm or other support 8 and has a finger 9 which projects horizontally from 30 the support, parallel to the track, and pointing in the direction of travel of the train. The guard is a flat plate which is pivoted to the part 5, as indicated at 10, and projects therefrom parallel to the finger 9, in spaced 35 relation therewith. A pin 11 carried by the inner end of the guard projects laterally therefrom and engages the finger 9, and thus limits the swing of the guard toward said finger.

40 In the finger 9 is a horizontal slot 12 in which the hook 6 is pivoted, as indicated at 13. The hook has a shank 14 carrying a ring 15 to facilitate the placing of the hook in operative position. The hook is pivoted 45 to swing in a horizontal plane and it is designed to be placed so as to project from one side of the finger into engagement with the guard 7. In the side of the guard which faces the finger is a recess 16 in which the 50 end of the finger is adapted to seat.

The guard 7 yieldingly engages the hook 6, the back of the former being pressed by

the free end of a bowed, resilient strip 17 carried by the part 5, the latter having a pin 18 which enters an aperture in one end 55 of the strip. The part 5 also carries a threaded stud 19 provided with a wing nut 20. The stud passes loosely through the strip and the wing nut is designed to be screwed down against the strip to vary the 60 degree of pressure of the latter against the guard.

In operation, the hook 6 is retracted and the ring of the mail-bag or pouch is placed between the parts 7 and 9, after which the 65 hook is swung to pass through the ring and to extend transversely between the parts 7 and 9, its free end seating in the recess 16. The guard 7 yieldingly engages the end of the hook and securely holds it in position to 70 support the mail-bag. When the catcher hook of the mail car strikes the bag, the sudden pull or jerk swings the hook forward whereby the ring on the bag slips off the hook and the bag is released and thrown 75 into the car.

The weight of the mail-bag or pouch does not affect tension of the guard 7 and the hook 6 is securely held in position to support the bag. The bag is released with ease 80 and without strain thereon.

I claim:

1. A mail bag holder comprising a body portion having a projecting finger, a pivoted hook carried by said finger and projecting from one side thereof, a pivoted guard member carried by the body portion and extending along the finger in spaced relation therewith, a pin carried by the guard member and engageable with the 90 finger for limiting the swing of said guard member in the direction of the finger, and means for yieldingly holding the guard member against the projecting end of the hook. 95

2. A mail bag holder comprising a body portion having a projecting finger, a pivoted hook carried by said finger and projecting from one side thereof, a pivoted guard member carried by the body portion 100 and extending along the finger in spaced relation therewith, means for yieldingly holding the guard member against the projecting end of the hook, said means compris-

ing a flat spring carried by the aforesaid body portion and having an aperture, a threaded pin carried by the body portion and passing through said aperture, and a 5 nut screwed on said pin and engageable with the spring to vary the degree of pressure of the latter against the guard member.

In testimony whereof I affix my signature in presence of two witnesses.

GEORGE IRA SHUMAKER.

Witnesses:

A. KUBICEK,
Mrs. A. KUBICEK.
